MAKING BIMETALLIC BILLET

Laurence J. Berkeley, Danville, Ill., assignor to Superior Steel Corporation, Pittsburgh, Pa., a corporation of Virginia

Application March 11, 1954, Serial No. 415,594

2 Claims. (Cl. 219—73)

This invention relates to the making of bimetallic billets. It relates particularly to a method of and apparatus for assembling and maintaining in assembly in proper cooperative relationship the components of a bimetallic billet.

I form a bimetallic billet by applying to a backing component which may, for example, be of carbon steel, a facing component or facing components which may, for example, be of gilding metal, copper, aluminum, stainless steel or other metal by applying the facing component or components to the backing component and holding the components in assembly by fastening means connected with the backing component at the edge faces thereof and extending into holding relationship with the facing component or components.

The fastening means at each edge face of the backing component may comprise a generally planar body portion lying against the backing component and means extending transversely of the general plane of the body portion engaging and holding in place the facing component or components. For example when a bimetallic billet is to be made comprising a backing component with facing components at opposite faces of the backing component the fastening means may comprise generally channel-shaped elements having their bodies or webs lying against the edge faces of the backing component and connected with the backing component, for example by welding, and having their holding portions or flanges extending substantially at right angles to the webs and overlying the edges of the facing components to clamp the facing components to the backing component. The channels may when applied to the backing component have their flanges extending at obtuse angles to the webs of the channels and the flanges may thereafter be pressed, for example by rolls, into clamping engagement with the facing components. The facing components may be narrower than the backing component to allow for differential lateral expansion. The pressure with which the flanges of the channels are pressed into clamping engagement with the facing components is controlled to allow for differential lateral expansion.

The fastening means may be applied to the backing component by continuous welding longitudinally of the assembly. The assembled backing component and fastening means (preferably with the facing component or components also assembled therewith) may be relatively moved in the direction of the length of the assembly in respect to welding apparatus; I prefer to mount the welding apparatus at a welding station and advance the work continuously through the welding station, although the work might be maintained in fixed position and a welder moved therewith. Each fastening element may be welded to the backing component by one or a plurality of welds; I prefer to weld fastening channels to the backing component by two continuous longitudinal welds at opposite sides of the longitudinal axis of each channel. I prefer to employ arc welding which fuses

a zone of the metal of the web of the fastening element completely through the web and a zone of the metal of the backing element contiguous to the first mentioned zone so that when the metal cools the fastening element is welded to the backing component by a substantially unitary metal connection. Supplemental weld metal may be added during the welding.

While the orientation of the work may be varied, I prefer to arrange the backing component in a horizontal plane with the facing component or components disposed against its top and/or bottom face or faces and to advance the assembly horizontally lengthwise through the welding station, the fastening means being applied to the generally vertical edge faces of the backing component.

For purposes of explanation and illustration I shall describe the making of a bimetallic billet comprising a relatively thick relatively wide elongated carbon steel backing component and two relatively thin relatively narrow elongated facing components of gilding metal, one of the facing components being somewhat thicker than the other but both being quite thin in relation to the backing component. I first dispose the thicker facing component in position and place the backing component atop it and then place the thinner facing component atop the backing component. The thus assembled components are advanced longitudinally, as, for example, on a roller table, to a station at which means are brought into engagement with the side edges of the components to insure that each of the three components is properly oriented in the line of advance of the assembly through the welding station and with each of the facing components laterally centered with respect to the backing component. Fastening channels are then applied to the side edge faces of the backing component, the flanges of the channels being initially disposed at obtuse angles to the web thereof so that the channels are slightly open in comparison with channels having their flanges at right angles to their webs. This is to facilitate application of the channels without interference by the facing components. Since one of the facing components is thicker than the other the channels must be positioned slightly off-center relatively to the backing component. The channels are set in place by hand and initially temporarily clamped to the backing component by hand clamps extending across the assembly and engaging the outsides of the webs of the respective channels.

The thus assembled components are advanced through the welding station. At the welding station the channels are clamped to the backing component by rolls so that the temporary hand clamps may be removed. In the present preferred embodiment of the apparatus herein disclosed two welds are formed between each channel and the backing component. Since the channels are arranged with their webs substantially vertical the welds extend substantially horizontally through the channels and into the vertical edge faces of the backing component, the welds for each channel being disposed one above the other and each weld being substantially continuous longitudinally of the billet. In the apparatus disclosed the welds are formed by arc welding. Each weld is formed by an electrode which draws an arc from the channel, the current passing through the channel and through the backing component to which another electrode extends to complete the electrical circuit. I prefer to form the weld by submerged arc welding and I apply flux, preferably in powdered form, during formation of the weld. The flux is supported by suitable means disposed in contiguity to the outer surfaces of the webs of the channels. I prefer to use generally horizontal endless belts which travel at substantially the same speed as the work, one belt for each weld disposed at

a level just below the level of the weld, the belts therefore being disposed at different elevations, the upper belt discharging its flux onto the lower belt. The upper weld is formed ahead of the lower weld so that flux from the upper weld may also be used in forming the lower weld. I provide means for recirculating and continuously supplying flux to the welds. The flux discharged by the upper belt onto the lower belt may be supplemental to additional flux supplied to the lower belt. I continuously supply welding rods constituting the electrodes which draw the arcs.

The flanges of the channels are rolled down into clamping engagement with the edges of the facing components, preferably after the channels have been welded to the backing component, the pressure applied being controlled so that the flanges tightly clamp the facing components to the backing component yet allow for differential lateral expansion, i. e., for lateral expansion of the facing components relatively to the backing component under the flanges of the channels. Unless such differential lateral expansion is provided for the facing components may bow up in the middle. The completed billet is delivered from the apparatus by suitable means such as a roller table and is ready for heating and hot rolling.

Other details, objects and advantages of the invention will become apparent as the following description of a present preferred embodiment thereof and a present preferred method of practicing the same proceeds.

In the accompanying drawings I have shown a present preferred embodiment of the invention and have illustrated a present preferred method of practicing the same, in which

Figure 28 is an enlarged longitudinal sectional view taken along line XXVIII—XXVIII of Figure 26; and

Figure 29 is a wiring diagram for the welding unit.

Referring now more particularly to the drawings, the apparatus, shown schematically in Figure 1, comprises generally an entrance conveyor 1, a welding unit 2, an exit conveyor 3 and crimping means 4.

Figures 22, 23, 24 and 25 are cross-sectional views showing details of the entrance conveyor 1. Rotatably mounted in bearings 221 in the frame of the conveyor is a transverse shaft 220 (Figures 7 and 22) having rollers 11 fixed thereon. The shaft is not driven but the rollers and shaft are free to turn when the assembly of billet components is advanced along the entrance conveyor by turning of the driven rollers 5 and 8. Drums 12 are mounted on the rollers 11 and fastened thereto by bolts 11a as shown in Figure 22. It will be noted (see, for example, Figure 8) that drums 12 are mounted not only on the rollers 11 carried by the shaft 220 but also on certain of the rollers 8. The drums are for positioning fastening channels as will presently be described. The shaft 220 has fixed thereto sleeves 222 inwardly of the bearings 221, and washers 223 surround the shaft and bear against the inner ends of the sleeves 222, the washers being held apart by a compression coil spring 224. Endless chains 225 pass over the sleeves 222 and dip into a pool of oil 226 contained in a reservoir 226a formed in the bottom of the entrance conveyor. Turning of the shaft 220 and the sleeves 222 causes the endless chains 225 to turn about the shaft and carry oil upwardly from the pool of oil 226. The oil is transferred from the chains to the sleeves and thence to the bearings 221.

Fixed to the shaft 10a of the motor 10 is a V-belt pulley 227 (Figures 7 and 25) driving V-belts 228. The

V-belts 228 extend about and drive a pulley 229 fixed to a shaft 230' mounted for rotation in bearings 234 in the frame of the conveyor. Also fixed to the shaft 230' is a gear 231. The gear 231 meshes with a gear 232' (Figure 7) fixed to a shaft 233' which is mounted for rotation in the frame. Through similar mechanism the motor 7 drives a shaft 233 mounted for rotation in the frame in bearings 235. A gear 231a similar to the gear 231 is fixed to the shaft 230 and meshes with a gear 232 fixed to the shaft 233 (Figures 7 and 24). The gear 232 dips into the pool of oil 226 for lubricating the gear train of which the gear 232 is a member. Some of the oil also passes to and lubricates the bearings 235. The gear train and bearings associated with the drive from the motor 10 are similarly lubricated.

Keyed to the shaft 233 is a sprocket 236 which drives an endless sprocket chain 237 which meshes with a sprocket 238 (Figures 7 and 23). The sprocket 238 is fixed to a shaft 239 which is journaled for rotation in bearings 240. The sprocket chain 237 carries oil from the pool of oil 226 to lubricate the associated working parts. Also fixed to shaft 239 is a sprocket 241 which drives an endless sprocket chain 242. The chain 242 meshes with a sprocket 243 fixed to a shaft 244 journaled for rotation in bearings 245.

Also fixed to the shaft 244 is a sprocket 246. Sprocket 246 drives an endless sprocket chain 247 which meshes with the sprocket 248 fixed to a shaft 249 journaled in the frame. In this way the shaft 249 is driven. Each of the shafts 244 and 249 has fixed thereto opposed rollers 5. When the shafts are driven the rollers turn and advance work disposed upon the rollers.

Also fixed to shaft 249 is a sprocket 250 which drives an endless chain 251 which meshes with a sprocket 251' fixed to a shaft 252. By a similar arrangement including an endless sprocket chain 254 a shaft 253 also journaled in the frame is driven by the shaft 252. Rollers 5 are also fixed to the shafts 252 and 253.

Mounted adjacent the entrance conveyor for cooperation therewith are two centering units 13 (Figures 18 and 19). The distance longitudinally of the conveyor between the two centering units 13 is somewhat less than the length of assemblies of billet components to be operated on by the apparatus. Each centering unit comprises opposed double-acting hydraulic cylinders 14 in which rams 15 operate. End plates 16 on the rams carry upper index blocks 17 and lower index blocks 18, which blocks are both removable and adjustable. When the upper facing component 19, the backing component 20, and the lower facing component 21 of an assembly to be formed into a bimetallic billet (Figure 2) are disposed on the conveyor in transverse alignment with the two rams the operator manipulates a valve (not shown) and hydraulic pressure is applied at the outer ends of the cylinders 14 forcing the rams 15 toward the center line of the entrance conveyor 1. The upper index blocks 17 engage the upper facing component 19, the bodies of the lower index blocks 18 engage the backing component 20 and projections 18a of the lower index blocks 18 engage the lower facing component 21. The blocks are replaceable and adjustable on the end plates 16 to properly cooperate with components of various sizes making up assemblies operated on by the apparatus. The two rams 15 of each centering unit 13 are interconnected through a linkage 22 shown in Figure 18 which maintains them equidistant from the center line of the entrance conveyor at all times. Thus when pressure is applied at the outer ends of the double-acting hydraulic cylinders 14 the index blocks 17 and 18 engage the upper and lower facing components and the backing component and center them with respect to each other and with respect to the center line of the entrance conveyor. After the components are centered by the two centering units the rams are retracted to free the assembly for further processing as will be explained.

The welding unit is generally shown in Figures 3A, 3B, 4A, 4B, 5 and 6. Double-acting hydraulic cylinders 23, 24, 25 and 26 are mounted in pairs on the frame 27 of the welding unit, there being two cylinders 23 one above the other at one side of the welding unit opposed by two cylinders 24 one above the other at the opposite side and there being two cylinders 25 one above the other at the first mentioned side of the welding unit in alignment longitudinally of the apparatus with the respective cylinders 24. Rams 28 operate in the cylinders. Mounted on the ends of the rams in the respective pairs of cylinders 23, 24, 25 and 26 are supports 29, 30, 31 and 32; that is, each support is carried by two vertically superimposed rams. Each of the supports 29, 30, 31 and 32 has upper and lower projecting portions 33 (Figure 20). Each portion 33 comprises a roller bearing 34. A shaft 35 is journaled in each vertically aligned pair of roller bearings 34. Cylindrical sections 36 and spacers 37 are mounted on each shaft 35 between members 33. The cylindrical sections are fastened in place on the shafts 35 by set screws 38. The cylindrical sections are grooved on the outside and have milled edges on the raised portions adapted to engage the assemblies as they move through the welding unit. Each of the entrance drive rolls 39, 40, 41 and 42 (Figures 3A and 3B) comprises the assembly of a shaft 35 with cylindrical sections 36 and spacers 37 thereon. Projecting from the upper portion 33 associated with entrance drive roll 39 is a rack 43 meshing with a pinion 44 rotatably mounted in a bracket 45 carried by the frame 27 (Figures 3A and 3B and 4A and 4B). A rack 46 similarly projects from the upper portion 33 associated with entrance drive roll 40 and meshes with pinion 44. Because of this interconnection the entrance drive rolls 39 and 40 must move inwardly and outwardly together and be at all times equidistant from the center line of the welding unit. The other entrance drive rolls 41 and 42 are similarly interconnected by racks 47 and 48 and pinion 49 and act cooperatively as do the rolls 39 and 40. A slot 50 is cut in the top of each shaft 35 (Figure 20) to accommodate the cross pin of a universal joint. The entrance drive roll 39 is driven by a universal joint 51 (Figure 4B) which fits over the end of shaft 35. The other end of the universal joint is connected to a member 52 which ends in a splined section 53 fitting inside and engaging tubular member 54 so as to be held against rotation but free to move longitudinally relatively thereto. Tubular member 54 is in turn driven through a universal joint 55 by a shaft 80 projecting downwardly from a train of gears (presently to be described) in a gear box 56. Thus the drive roll 39 may be driven regardless of the position of rams 28. The universal joints will transmit power when the members 52 and 54 are at any angle relatively to the gear box and drive roll. The extensible shaft comprising members 52 and 54 will adjust itself to any required length. The remaining entrance drive rolls 40, 41 and 42 are similarly driven from the gear box 56. Attached to the shaft 56a of an electric motor 57 (Figures 12 and 13) is a split pulley comprising opposed cooperating halves or sections 58 and 59. Pulley section 58 is fixed to the motor shaft. Pulley section 59 is splined to the motor shaft so as to be held against rotation but free to move longitudinally relatively thereto. Pulley section 59 is resiliently urged toward pulley section 58 by a spring attached to the outer end of the motor shaft and located within the hollow cover 60. The peripheral faces of the two pulley sections 58 and 59 are tapered and converge toward the motor shaft. A belt 61 is disposed about the split pulley. As pulley section 59 moves away from pulley section 58 the effective diameter of the split pulley is reduced and belt 61 will be

allowed to more closely approach the motor shaft. Belt 61 is also disposed about a conventional pulley 62 fastened to a shaft 63. The motor 57 is mounted on a bracket 64 carried by a generally upstanding frame 65 for generally vertical sliding movement relatively thereto. The frame 65 is carried by the welding unit frame 27. Rotatably mounted in frame 65 is a generally vertical threaded shaft 66 which is rotated by turning hand wheel 67 which is fixed to the shaft at the upper end thereof. The threaded shaft 66 passes through portions 66a of the bracket 64 which are drilled and tapped to engage with the threads of shaft 66. By rotating shaft 66 the bracket 64 and hence the motor 57 carried thereby may be raised or lowered with respect to frame 65. As the motor moves upwardly the tension on belt 61 increases, causing the pulley section 59 to move outwardly against the action of the spring in the hollow cover 60, thereby reducing the effective diameter of the pulley. This in turn reduces the speed at which the driven shaft 63 is rotated. Conversely, as the motor moves downwardly relatively to the frame 65 the tension on belt 61 decreases, allowing the spring to move the pulley section 59 toward the pulley section 58 and increases the effective diameter of the pulley. This in turn increases the speed at which the driven shaft 63 is rotated.

Also fixed to shaft 63 is a sprocket 68 with which an endless sprocket chain 69 meshes. The endless sprocket chain 69 also meshes with another sprocket 70 fixed to the shaft 70a of an oil pump 71. The oil pump recirculates oil from the sump of gear box 56 over the gears therein.

Shaft 63 (Figures 26 and 27) has a portion thereof formed as a worm 72 which meshes with a worm wheel 73 fixed to a shaft 73a. The shaft 73a in turn drives the gears 74, 75, 76, 77, 78 and 79 through the gear train in the gear box 56. The direction of turning of the respective gears is indicated by arrows in Figure 26. Gear 74 is fixed to the previously mentioned shaft 80 which projects from the lower side of the gear box (Figure 4B) and drives entrance drive roll 39 through the universal joints 51 and 55 and connecting members 52 and 54. In like manner gears 75, 76 and 77 drive entrance drive rolls 41 and 42, respectively. Thus the motor 57 drives the four entrance drive rolls simultaneously. The gear train is designed so that the entrance drive rolls are all driven at the same speed and in respective directions to advance an assembly of billet components through the welding unit from left to right viewing Figure 1 when the rolls are in driving engagement with the assembly as will be described.

Generally opposed double-acting hydraulic cylinders 81 and 82 are mounted on frame 27 (Figures 3A and 3B). Rams 83 project from the inner ends of the respective cylinders. Each ram 83 carries a support 84 which in turn carries roller bearings 86 (Figure 21) in which is journaled a shaft 87. Fixed to the lower end of each shaft 87 is an exit drive roll; the opposed exit drive rolls are designated 89 and 90, respectively (Figures 3A, 3B and 21). The exit drive rolls are milled as indicated at 88a in Figure 21 to engage the assemblies (then completed billets) being driven out of the welding unit. The exit drive rolls 89 and 90 are driven respectively by gears 78 and 79 (Figure 26) through universal joints and extensible shafts similarly to the entrance drive rolls. Gears 78 and 79 are driven at the same speed as gears 74, 75, 76 and 77 by using appropriate gearing between them. The rams 83 carry opposed racks 90a and 90b meshing with a pinion 90c as shown in Figures 3A and 3B whereby to insure that the exit drive rolls 89 and 90 are at all times equidistant from the center line of the welder.

The frame 27 carries at each side a support 91 (Figures 4A and 4B) carrying for guided longitudinal movement transversely of the welder a rack 93. Meshing with each

rack 93 is a pinion 96 fixed to a shaft 95 journaled in the corresponding support 91 and which shaft is turned by a hand wheel 99 (Figures 3A and 3B) through gearing in a gear case 98. Turning of either hand wheel 99 will independently move the corresponding rack 93 toward or away from the center line of the welder.

Connected with each rack 93 is a support 109 upon which is mounted an electric motor 101. Each motor 101 drives through reduction gearing in a gear case 102 a shaft 103 which through a coupling 104 drives a shaft 105. Each shaft 105 is connected through a universal joint 108 with a shaft 107 which in turn is connected through a universal joint 109 with a shaft 156' for driving the corresponding upper flux belt 106 (Figures 6, 14, 15 and 16). Fixed to each shaft 103 is a sprocket 109b with which meshes a sprocket chain 111 which also meshes with a sprocket 111a fixed to a shaft 110 journaled in the corresponding support 100. Each shaft 110 drives the corresponding lower flux belt 112 (Figures 6, 14, 15 and 16) through universal joint 114, shaft 113, universal joint 115 and shaft 156. By the mechanism thus provided the flux belts may be adjusted in position toward and away from the center line of the welder while being continuously connected with their driving means.

At each side of the welder the upper flux belt assembly is carried by a support 126 (Figures 14, 15 and 16) which in turn is carried by a vertical rack 125 (Figures 4A and 4B) mounted for vertical movement on the corresponding horizontal rack 93. Each rack 125 is moved up or down by a pinion 122 (Figure 5) meshing therewith, the pinion being fixed to a shaft 120 journaled on the corresponding rack 93. The outer end of each shaft 120 is squared as shown at 121 to receive a wrench for turning the shaft. Turning of either shaft 120 thus changes the elevation of the upper flux belt assembly at the corresponding side of the welder. The change in elevation of an upper flux belt assembly does not interfere with driving of the corresponding upper flux belt 106 through the mechanism above described since the universal joints compensate for changes in elevation of the belt.

Similarly the lower flux belt assembly at each side of the welder is carried by a bracket 134 (Figures 14, 15 and 16) which in turn is carried by a vertical rack 132 (Figure 5) mounted for vertical movement on the corresponding horizontal rack 93 similarly to the vertical racks 125. Meshing with each vertical rack 132 is a pinion 130 fixed to a horizontal shaft 127 journaled for rotation in the corresponding horizontal rack 93. The end of each shaft 127 is squared as shown at 127a to receive a wrench for turning the shaft. Thus the lower flux belt assemblies are mounted and vertically adjustable analogously to the corresponding upper flux belt assemblies.

Figures 14, 15 and 16 show the upper and lower flux belt assemblies at the right hand side of the welding unit viewing Figures 4A and 4B. Fixedly mounted on the bracket 134 is a bearing bracket 135 in which is journaled for rotation the shaft 156 carrying a pulley 137 about which the lower flux belt 112 is trained. Four bolts 138 are threaded into the bearing bracket 135. Surrounding each bolt is a bushing 139. Atop the bushings 139 and held down by the heads of the bolts is a plate 143. Disposed about each bushing 139 are upper and lower grooved rollers 140 and 141 with a spacer 142 therebetween as shown in Figures 14 and 16. The total axial dimension of the rollers 140 and 141 and the spacer 142 disposed about each bushing 139 is slightly less than the axial dimension of the bushing so that the rollers are free to turn about the bushing.

A second bearing bracket 144 has journaled therein a shaft 145 carrying a pulley 146 about which the lower flux belt 112 is also trained as shown in Figure 14. The bearing bracket 144 has a portion passing between the opposed lower grooved rollers 141 and entering the

grooves thereof so that the bearing bracket 144 is in effect mounted in the rollers 141 for movement generally in the direction of the length of the belt 112. A compression coil spring 148 is compressed between a shoulder 148a of the bearing bracket 135 and a receiving portion 147 of the bearing bracket 144 and resiliently urges the bearing bracket 144 toward the right viewing Figure 14 relatively to the bearing bracket 135 whereby to continuously resiliently urge apart the pulleys 137 and 146 and thereby maintain the belt 112 taut.

Bolted to the bracket 134 by bolts 134a is a block 149 which is drilled to slidably accommodate a bolt 150. Threaded onto the end of the bolt 150 as shown in Figure 16 is a block 151 to which a flux belt support plate 152 is fastened by bolts 152a. The flux belt support plate 152 has a portion passing between the opposed upper grooved rollers 140 and entering the grooves thereof so that the flux belt support plate is in effect mounted in the rollers 140 for movement generally transversely of the belt 112. The flux belt support plate 152 directly underlies the upper reach of the belt 112 as shown in Figures 14 and 16.

Surrounding the bolt 150 between the blocks 149 and 151 is a compression coil spring 153 compressed and bearing between the blocks 149 and 151 as shown in Figure 16. The spring 153 urges the flux belt support plate 152 toward the right viewing Figure 16 or toward the assembly of billet components being welded. It resiliently presses the flux belt support plate against the assembly as it advances through the welding unit but by reason of the provision of the spring 153 allows for variations in the engaging edge of the assembly. The extreme inner position to which the flux belt support plate 152 may move may be adjusted by turning the bolt 150 relatively to the block 151. The extreme inner position of the flux belt support plate is reached when the head of the bolt 150 engages the block 149. Bolted to the flux belt support plate 152 is a backing member 154 (Figures 14, 15 and 16) which is provided with an opening 155 to accommodate the lower welding electrode.

As previously stated, shaft 156 is driven by the motor 101 through the mechanism shown in Figures 3A and 4A. The shaft 156 drives the lower flux belt 112 in the direction such that its upper reach moves in the direction of advance of the assembly being welded. The speed of the motor 101 is controlled so that the upper reach of the belt advances at the same speed as the work.

The bracket 134 is inclined to the horizontal so that the inside edge of the upper reach of the belt 112 is in juxtaposition to the assembly during welding while the inside edge 159 of the lower reach of the belt is spaced from the assembly. The tilting of the belt has a two-fold function; it minimizes wear on the inside edge 159 of the lower reach of the belt which during the welding operation moves in the direction opposite of the direction of advance of the work. Moreover, the slope of the belt toward the work tends to pile the powdered flux riding upon the belt against the side of the assembly and around the weld.

I have described above in detail the mounting and operation of the lower flux belt 112 at one side of the welding unit. The lower flux belt 112 at the opposite side of the welding unit is mounted and operated in the same manner. The same reference numerals are applied to parts which are duplicated at both sides of the welding unit. Moreover, the upper flux belts 106 are mounted and operated analogously to the lower belts 112. Parts of the upper belt assemblies corresponding to parts of the lower belt assemblies are designated by corresponding reference numerals each having a prime affixed.

Adjacent the flux receiving end of each of the upper flux belts 106 there is provided a flux retainer 169 which is fastened to the corresponding backing member 154' to prevent flux from falling off of the end of the belt. This

is shown in Figure 14 in which it will be understood that the upper reaches of both belts move from right to left.

Mounted upon the outer end of each of the brackets 126 and 134 (Figures 3B, 4A, 4B and 17) is a welding head which may be of conventional design and which feeds a welding rod or electrode to the work at controlled speed. There are four identical welding heads each designated generally by the letter W which I purchase from a manufacturer of such equipment. The welding heads feed welding rods 161 from coils which are not shown in the drawings through insulating tubes 162 to the point of the weld. Each of the insulating tubes 162 extends to and within one of the openings 155 or 155' shown in Figure 14. Each welding head W is insulated from the bracket 126 or 134 carrying it by an insulating pad 163. The welding rod 161 is fed by rollers 164 and 165 between which it passes, the welding head being provided with adjustable means for driving the rollers at desired speed. Since the mechanism for feeding the welding rods is known to those skilled in the art it will not be described in detail. Each welding rod 161 is connected to a source of electric current which is insulated from the frame of the apparatus. The current passes through the welding rod within the insulating tube and draws an arc at the point of welding.

At each side of the welding unit (Figures 4A, 4B and 6) is a hopper 170 containing powdered flux. Each hopper 170 delivers powdered flux by gravity through two delivery tubes designated 172 and 173 respectively (Figure 30 6). The rate of flow of flux through each of the delivery tubes 172 and 173 is controlled by an adjustable gate 174. The delivery tube 172 supplies powdered flux to the upper flux belt 106 at the corresponding side of the welding unit so as to cover the weld being effected by the upper 35 welding rod or electrode 161. The flux covers the weld at the time of welding (the technique employed with respect to flux application is known to those skilled in the art as "submerged arc welding") and flux is carried along upon the belt 106 which as above explained advances in 40 the direction of advance of the work and at the same speed. Thus the weld is maintained submerged in flux until the metal has solidified.

Flux from the upper belt 106 at each side of the welding unit is delivered onto the corresponding lower belt 45 112 at the region of the lower weld and is supplemented by additional flux delivered through the delivery tube 173 (Figure 6). The weld effected by the lower electrode or welding rod 161 is formed analogously to the upper weld, the weld being maintained submerged in flux until the 50 metal has solidified.

The flux is dumped off of the delivery end of the lower flux belt 112 at each side of the welding unit where it may be received by any suitable apparatus (not shown) and recirculated to the hoppers 170.

55 The exit conveyor 3 (Figures 1, 9 and 10) is similar in construction and operation to the entrance conveyor 1. Rollers 177 are driven through endless chains 178 by electric motor 179 and rollers 180 are driven through endless chains 181 by electric motor 182. Rollers 183 are not driven but are free to rotate.

Engaging the second and third sets of rollers away from the welding unit in the entrance conveyor 1 (Figures 7 and 8) are grounding brushes 184. Each of the grounding brushes 184 is connected with a ground strap 185 which is electrically connected to the frame. Similar brushes and ground straps are associated with the two sets of rollers in the exit conveyor 3 nearest the welding unit (Figures 9 and 10). The grounding brushes and straps serve to make an electrical connection from the associated rollers to the frame. When an electric arc is drawn at the welding point the current passes through the welding rod to the arc and from the arc through the work to the rollers and thence through the brushes and ground straps to the frame to complete the electrical cir-

cuit. One side of the source of current is grounded to the frame and the other side is connected to the electrodes.

Mounted in the path of the work as it advances through the welding unit are six electrical switches designated respectively 188, 193, 196, 197, 200 and 201 which are shown in Figure 6 and which are also shown in the wiring diagram Figure 29. As the work advances from left to right viewing Figure 6 the switches are successively operated thereby. They may be positioned at any portion of the path of the work so that as the work moves through the welding unit some part of its engages and operates the switches one after the other.

The first switch which the work or assembly of billet components will operate is switch 188. That switch is normally held in its open position with the switch arm extending generally upwardly as shown in Figure 6 by a spring which is not shown in the drawings. When the work in advancing toward the right (Figure 6) depresses the arm of switch 188 it closes a circuit (Figure 29) through the coil 189 of a solenoid-operated valve 190. In Figure 29 the reference numerals 186 and 187 represent respectively the two conductors of an electrical power line. Energizing of the coil 189 opens the valve 190 and allows hydraulic fluid under pressure to move under the action of a pump (not shown) in the direction of the arrow in Figure 29 to a manually operable valve 191 which is operated by the welder or a helper. The manually operable valve is a three-position valve. In its central or "by-pass" position it simply by-passes the hydraulic fluid back to the pump. In its "open" position it supplies hydraulic fluid to the inner ends of the double-acting hydraulic cylinders 23, 24, 25 and 26. In its "closed" position it supplies hydraulic fluid to the outer ends of those cylinders. As the work approaches the rolls 39, 40, 41 and 42 are separated to allow the forward end of the work to pass therebetween whereupon through operation of the switch 188 and moving of the manually operable switch 191 to the "close" position the rolls are moved inwardly to engage and positively guide and advance the work through the welding unit. A push button switch 192 is provided which is in parallel with the switch 188 and which the operator may employ to move the rolls when an assembly of billet components is approaching the welding unit but has not yet depressed the arm of the switch 188 to operate that switch.

As the assembly passes beyond switch 188 it next depresses the arm of switch 193 and operates that switch. The arm of switch 193 like that of switch 188 is normally held in the position shown in Figure 6 by a spring. When the switch 193 is operated it closes a circuit to energize the coil 194 of the upper electrode welding circuit relay 195 to bring about closing of the welding circuit from the source of current to the upper electrodes.

Switch 196 is wired in parallel with switch 193 and likewise normally held by a spring in its open position with its arm extending generally upwardly.

Switch 197 is similar to the previously described switches in that it is normally held by a spring in open position with its arm extending generally upwardly as shown in Figure 6. When the switch arm is depressed by the work the switch 197 closes and completes a circuit to energize the coil 198 of the lower electrode welding circuit relay 199 to bring about closing of the welding circuit from the source of current to the lower electrodes.

Switch 200 is wired in parallel with switch 197 and, like the other switches described, is normally held by a spring in its open position with its arm extending generally upwardly.

Switch 201 is a double throw switch which is normally held by a spring in its upper position with its arm extending generally upwardly as shown in Figure 6 and as indicated by the solid line in Figure 29. When the arm of switch 201 is depressed the switch moves to the position indicated by the dotted line in Figure 29 and completes a circuit through the coil 202 of a solenoid-operated hy-

draulic valve 203. This moves the valve 203 to its "close" position to admit hydraulic fluid under pressure to the outer ends of the double-acting hydraulic cylinders 81 and 82 forcing the exit drive rolls 89 and 90 to close on the assembly. When the assembly has passed beyond the switch 201 onto the exit conveyor the switch is returned to its normal position by its spring, completing a circuit through push button switch 204 (which is normally held closed by a spring 204a) and through the coil 205 of the solenoid-operated hydraulic valve 203. This moves the valve 203 to its "open" position in which hydraulic fluid under pressure is admitted to the inner ends of the double-acting hydraulic cylinders 81 and 82 to move the exit drive rolls 89 and 90 to their outermost or inoperative positions. When the exit drive rolls 89 and 90 reach their outermost positions a portion (not shown) of one of the roll supports engages and opens the push button switch 204 against the action of the spring 204a, breaking the circuit through the coil 205. This permits the valve 203 to move to the "by-pass" position under the action of a spring within the valve casing.

Switches 188, 193, 196, 197, 200 and 201 are mounted alternately on opposite sides of the center line of the welding unit. The timing of the various operations can be adjusted by appropriate change in position of the switches.

The crimping means is disposed at the delivery end of the exit conveyor 3 as shown in Figure 1. The crimping means is shown in elevational view to enlarged scale in Figure 11. It comprises roll housings 206 in which are journaled for rotation one above the other an upper crimping roll 207 and a lower crimping roll 208. The upper crimping roll 207 has spaced apart radial crimping flanges 207a and the lower crimping roll 208 has spaced apart radial crimping flanges 208a; the axial distance between the flanges 207a is the same as the axial distance between the flanges 208a, and the respective flanges 207a are disposed directly above the respective flanges 208a.

The crimping rolls 207 and 208 are driven by an electric motor 212. The motor 212 drives through a belt 213 gearing in a gear case 210, the gearing being connected with the respective crimping rolls 207 and 208 by shafts 209 and 211 respectively. The crimping roll 208 is mounted in position to turn about a fixed axis in the roll housings 206 while the crimping roll 207 and the bearings therefor are movable up and down in the roll housings to alter the distance between the crimping rolls. For this reason the driving shaft 209 for the crimping roll 207 has universal joints 209a at its ends where it is connected respectively with the gearing in the gear case 210 and with the crimping roll 207.

The bearings for the crimping roll 207 are movable vertically in the roll housings 206 by screws which are not shown in the drawing but are conventional. The screws are rotated by an electric motor 214 through suitable gearing as well known to those skilled in the rolling art. Thus the distance between the crimping rolls 207 and 208 may be adjusted as desired without disconnecting the crimping rolls from their driving means.

I shall now describe a cycle of operations employing the apparatus above described in the formation of a bimetallic billet. I assemble the lower facing component 21, the backing component 20 and the upper facing component 19 of the bimetallic billet upon a roller table which is not shown in the drawings and which forms no part of my invention. The roller table is positioned to the left of the entrance conveyor 1 viewing Figure 1. I form the assembly of the billet components 19, 20 and 21 by first placing the lower facing component 21 upon the roller table, then placing the backing component 20 upon the lower facing component 21 and then placing the upper facing component 19 upon the backing component 20. I then move the assembly toward the right viewing Figure 1 onto the entrance conveyor 1 and to a position in which the longitudinal center of the assembly approximately coincides with a point midway between the two centering

units 13 as indicated by chain lines in Figure 8. The operator then moves the rams of the centering unit inwardly and the index blocks will center the three components with respect to each other and with respect to the center line of the entrance conveyor as above described. After centering the components the rams of the centering units are withdrawn and the assembly lies properly centered upon the entrance conveyor.

The entrance conveyor is operated to advance the assembly until the front end of the assembly is close to the welding unit 2 with the longitudinal mid-portion of the assembly substantially overlying the intermediate set of the three sets of drums 12. The assembly is stopped at that point. Two channels 215 (Figure 2) are then placed one on each side of the entrance conveyor on the drums 12 in substantially upright positions with their upper flanges generally above the upper edges of the upper facing component 19 and their lower flanges resting on the drums 12 and generally below the lower edges of the lower facing component 21 as shown in Figure 22. At that time the channels are somewhat open and do not engage, or at least do not holdingly engage, the facing components 19 and 21. The channels are fastened in position by hand clamps spanning the assembly and pressing inwardly against the outer faces of the webs of the channels.

The assembly is then advanced into the welder by operation of the electric motor 10 which drives rollers 8. When the forward end of the assembly is disposed between the entrance drive rolls 39, 40, 41 and 42 the assembly may be stopped and the operator may, if desired, move the entrance drive rolls inwardly through use of the push button switch 192 and the manually operated hydraulic valve 191. The valve 191 may be moved to "close" position whereupon the push button switch 192 may be closed, resulting in movement of the entrance drive rolls 39, 40, 41 and 42 inwardly to engage the assembly. Alternatively the assembly may be advanced by the entrance conveyor until the switch 188 is closed which automatically closes the entrance drive rolls 39, 40, 41 and 42 upon the assembly.

When the four entrance drive rolls 39, 40, 41 and 42 are closed upon the assembly the milled edges 36a thereof will bear against the outer faces of the webs of the channels 215 at vertically spaced zones and will press the channels firmly against the backing component 20 while at the same time advancing the assembly through the welding unit. The motor 57 (Figures 12 and 13) will be operated when the entrance drive rolls are in engagement with the assembly to turn the drive rolls to advance the assembly through the welding unit. After the entrance drive rolls engage the channels the hand clamps may be removed. Desirably the hand clamps are removed one by one as the assembly moves into the welding unit, the forward clamp being removed first and so on rearwardly.

As the assembly advances through the welding unit it closes switch 193 which operates relay 195 and completes the welding circuit to the two upper electrodes 161, i. e., the electrodes which project through the openings 155'. The switch 193 is closed shortly before the leading end of the assembly reaches the two upper welding electrodes 161. I prefer to tack-weld a small piece of metal to the front end of each of the channels 215 so that the arcs which are initially struck between the tips of the electrodes and the assembly do not pit the metal of the assembly proper. Any pitting is in the small pieces of metal tack-welded to the front ends of the channels. At the conclusion of the welding operation the small pieces of metal can be knocked off. Consequently the welding is in progress with the welds submerged in the flux when the leading edges of the channels reach the welding zone.

When the small pieces of metal tack-welded to the front ends of the channels 215 come opposite the upper

electrodes 161 arcs are struck from the ends of the electrodes to the small pieces of metal, the electrical circuit in the case of each electrode being completed through the grounded rollers of the entrance and exit conveyors. 5 The welding circuit for each of the upper electrodes is from the source of current through the electrode, across the arc, through the assembly, through the grounded rollers and the frame and back to the source of current. The arcs from the upper electrodes 161 generate heat which melts completely through the webs of the channels 215 and into the backing component 20, forming upper welds 216 as shown in Figure 2.

The above description of the formation of the upper welds 216 applies also to the formation of the lower welds 217 (Figure 2), the lower welds being formed by 10 the lower electrodes 161 which project through the openings 155. The two lower electrodes are energized by engagement of the assembly with the switch 197. In both cases the heat of the arcs melts completely through the webs of the channels and melts portions of the metal of the backing component; there are formed continuous molten pools submerged in the flux, the molten pools being made up of metal of the channels, metal of the backing component and metal of the electrodes. Thus 15 I form in the vertical faces of the work submerged arc welds. When the pools of molten metal solidify they in effect integrate the channels 215 with the backing component 20.

As the assembly approaches the electrodes the operator 20 opens the adjustable gates 174 and allows flux to flow from the supply hoppers 170 onto the belts 105 and 112. The flux is by the belts maintained against the webs of the channels and maintains the welds submerged during formation and until the metal has substantially solidified. 25 The backing plates 154 and 154' as well as the tilt of the belts aids in maintaining the flux effectively about the welds. The flux substantially isolates the welds from the atmosphere and insures sound welds extending generally horizontally into the assembly. The welds penetrate the 30 backing component 20 deeply enough to maintain the channels securely in place.

The upper welding electrodes continue to be energized until the trailing end of the assembly passes beyond and releases the switch 196. Preferably the switch 196 is 35 positioned so that the welding circuit is not broken until the arcs from the upper welds have been extinguished by movement of the assembly away from the upper electrodes a distance greater than the gaps which the arcs will span. The same applies with respect to opening of 40 the welding circuit for the lower electrodes by operation of the switch 200 when the trailing edge of the assembly passes thereover.

As the leading end of the assembly passes over and 45 operates switch 201 the coil 202 will be energized and the solenoid-operated hydraulic valve 203 will admit oil under pressure to the outer ends of the double-acting hydraulic cylinders 81 and 82 to move the exit drive rolls 89 and 90 into driving engagement with the assembly. The exit drive rolls 89 and 90 deliver the welded assembly from the welding unit after its trailing end has passed 50 beyond the entrance drive rolls. After the trailing end of the welded assembly has passed beyond the entrance drive rolls the operator may return those rolls to their outward inoperative position by operating push button switch 192 with the manually operated hydraulic valve 55 191 in "open" position.

As the trailing end of the welded assembly releases 60 switch 201 that switch will be returned to its upper position and energize coil 205 which will cause valve 203 to admit hydraulic fluid under pressure to the inner ends of the double-acting hydraulic cylinders 81 and 82 whereby to return the exit drive rolls 89 and 90 to their outer inoperative positions. The welded assembly is then 65 disposed upon the exit conveyor 3. It is moved upon the exit conveyor to and through the crimping rolls 207 and 208.

The upper crimping roll 207 is adjusted relatively to the lower crimping roll 208 so that when the welded assembly passes between the crimping rolls the flanges 207a and 208a of the crimping rolls, which may be milled if desired, press the flanges 218 of the channels 215 into crimping engagement with the facing components 19 and 21. However, the crimping pressure is regulated so that the facing components may expand beneath the flanges 218 relatively to the backing component when the billet is heated. The facing components are by my method and by use of my apparatus centered with respect to the backing component leaving spaces 219 of substantially uniform width at the opposite edges of the facing components to allow for differential expansion. The completed billet ready for heating and hot rolling is delivered from the crimping rolls 207 and 208.

In operations which have proved highly successful I have used for welding alternating current of an amperage varying from three hundred to one thousand amperes with a potential varying up to sixty volts. The linear speed of welding may be any speed up to about forty inches per minute. The holding members or channels which I have employed have been from $\frac{1}{16}$ inch to $\frac{3}{8}$ inch thick and the depth of penetration of the weld into the backing component has been from $\frac{3}{16}$ inch to $\frac{3}{8}$ inch. I have used with success a granulated chemically stable flux containing alkaline earth silicates, a flux which is prefused and ground after fusing being found to obtain excellent results. The flux may contain the silicates of manganese, sodium and calcium. Other fluxes may be employed.

While I have shown and described a present preferred embodiment of the invention and have illustrated a present preferred method of practicing the same it is to be distinctly understood that the invention is not limited thereto but may be otherwise variously embodied and practiced within the scope of the following claims.

I claim:

1. A method of making a bimetallic billet comprising disposing a backing component and facing components at opposite faces thereof in face-to-face relationship with the opposed faces substantially horizontal, disposing channels each having a web and flanges for holding the components together with their webs in generally vertical position against the backing component at opposite sides of the backing component but with their flanges out of firm holding relationship with the facing components, advancing the assembled components and channels, during such advance supporting and advancing with the assembled components and channels two masses of flux at different elevations against the outside face of the web of each of the channels, during such advance progressively drawing arcs from the outside faces of the webs of the channels within each of the four masses of flux and thereby in regions protected from the atmosphere melting zones completely

through the webs of the channels and into the backing component to integrate the channels to the backing component, delivering flux from the upper mass of flux against the outside face of the web of each channel for reuse in the corresponding lower mass of flux and crimping the flanges of the channels into firm holding relationship with the facing components.

2. A method of making a bimetallic billet comprising disposing a backing component and a facing component in face-to-face relationship with the opposed faces substantially horizontal, disposing members each having a web and a flange for holding the components together with their webs in generally vertical position against the backing component at opposite sides of the backing component but with their flanges out of firm holding relationship with the facing component, advancing the assembled components and flanged members, during such advance supporting and advancing with the assembled components and flanged members two masses of flux at different elevations against the outside face of the web of each of the flanged members, during such advance progressively drawing arcs from the outside faces of the webs of the flanged members within each of the four masses of flux and thereby in regions protected from the atmosphere melting zones completely through the webs of the flanged members and into the backing component to integrate the flanged members to the backing component, delivering flux from the upper mass of flux against the outside face of the web of each flanged member for reuse in the corresponding lower mass of flux and crimping the flanges of the flanged members into firm holding relationship with the facing component.
